TRUSS PAD

Filed Sept. 10, 1928

Walter B. Seeley
By Cyrus W. Anderson
Attorney

UNITED STATES PATENT OFFICE

WALTER B. SEELEY, OF PHILADELPHIA, PENNSYLVANIA

TRUSS PAD

Application filed September 10, 1928. Serial No. 304,887.

My invention relates to pads for trusses which are used for the treatment of hernia. A truss of the character to which my invention relates and for which a pad embodying my invention is particularly adapted, may be defined as an appliance consisting of a belt or an elastic steel spring encircling the body, to which is attached a pad used in cases of rupture to hinder the descent of the parts.

In the use of trusses it is desirable to employ pads therefor having means whereby a more effective application of the pad may be made to the specific portion of the body affected than heretofore has been practical.

The general object of my invention is to provide a pad for embodiment in a truss structure having novel features of construction, whereby when applied it will operate with great efficiency in the prevention of the descent or protrusion of the viscera or other organs of the body through either a natural opening from a cavity or one accidentally torn therein.

It also is an object of the invention to provide a pad of novel construction for trusses, comprising a plurality of pad members one of which is adapted to be removed to permit use of the other alone.

Another object of my invention is to provide a pad comprising a main body part adapted to receive interchangeably any one of a plurality of supplemental pads which may be of different sizes and shapes.

I shall not attempt to set forth at this time all of the various objects and advantages appurtenant to my invention, but other objects and advantages thereof either will be specifically referred to in the detailed description which follows or will be apparent from such description.

In order that the invention may be readily understood and its many practical advantages fully appreciated reference should be had to the accompanying drawing in which I have illustrated one embodiment thereof in a form which is at present preferred by me, but it will be understood that changes in the details of construction and

in the arrangement and conformation of parts may be made within the scope of the claims without departing from the invention or the principle thereof.

In the drawing:

Fig. 1 is a view in horizontal transverse section of a truss pad embodying the invention, a portion of the strap or brace by which the truss is secured to the body being shown partly in section and partly in edge elevation;

Fig. 2 is a view in elevation of the wearing or contact face of the pad;

Fig. 3 is a view of the opposite side or face of the pad;

Fig. 4 is a view in side elevation of the supplemental attached pad shown in Figs. 1 and 2, removed from its position upon the main or larger pad; and

Figs. 5 and 6 are similar views showing removable and interchangeable pads of different sizes from the pads shown in Figs. 1, 2, and 4.

In the drawing I have shown a pad structure, comprising pads 1 and 2, the latter being removably mounted upon the former. The pad 1 is of the usual size of pads of the character employed in truss structures and may consist of any suitable material, such as vulcanized rubber, which should have the requisite or desired elasticity. The pad 2 is very much smaller and presents a much smaller surface wearing area than the pad 1, and when the truss is worn is adapted to be seated directly over the opening or rupture which it is desired to close. The said pad 2 being relatively small will sink into the flesh and project inwardly, perhaps causing portions of the body located outwardly of or over the opening or rupture to enter the latter and thus more effectually close the same.

The surface portion of the pad 1 surrounding the edge of the pad 2 contacts or may contact with the portion of the body surrounding that with which the pad 2 is in contact and thereby serves as a means to limit the penetration of the pad 2. The material of the pad 2 may be and usually is the same as that of the pad 1, and in any case such

material may be of a character which has been or may be found suitable for use in the construction of truss pads.

The pad 1 is molded around a plate 3 the edges of which are of oval outline, as indicated by the dash lines 4 in Figs. 2 and 3. The said plate is provided with a central outwardly projecting portion 5 from the edge of which an inwardly inclined portion 6 extends which terminates in a laterally and reversely extended portion 7 constituting a brim-like portion. By thus shaping the plate 5 its strength is greatly enhanced, whereby the possibility of deformation thereof during the use of the pad is reduced to a minimum. At the same time the resilience or spring effect of the plate is increased, which is a desirable characteristic. A hollow stem metal member 8 is secured at its outer end in an opening 9 formed at the center of the plate 3, which stem extends inwardly of the pad 1 toward the opposite side thereof. The stem 8 is provided with an axial opening which extends therethrough, which opening is in alignment with an opening 10 which extends entirely through the pad 1 and terminates upon the inner wearing surface thereof. Preferably the inner end of the stem 8 is provided with a flange 11 whereby it is more securely anchored within the pad 1. The wall of the outer end portion of the stem is thickened and the opening through the said portion of the stem is provided with screw threads as indicated at 12.

For the purpose of removably securing the pad 2 upon the pad 1 I have provided the former with a stem 15 having a curved plate 16 secured to one end thereof, which curved plate and an adjoining portion of the said stem are imbedded within the body of the said pad 2. The outer or free end of the stem 15 is provided with slots 17 which preferably extend at right angles to each other as indicated, to divide the same into four segments 18, as indicated in Fig. 2 of the drawing, which segments are adapted to be slightly spread so that when the said outer free end of the stem is inserted into the opening of the stem 8 it is retained therein by the friction of the stem, particularly the spread segments thereof, against the surface of the said opening.

It will be understood that pads 2 of different sizes may be substituted for and interchanged with the pad 2 shown in position in Fig. 1. In Figs. 5 and 6 I have shown pads like that shown in Fig. 4, but of different sizes.

It will be understood that owing to variations in the sizes of the openings to be closed and to be treated by a pad it is very important that means be provided for meeting the variable conditions to which variations in the

sizes of the said openings or ruptures may give rise.

In the construction as illustrated the pad 2 is shown as being circular in outline. Such shape is clearly shown in Fig. 2 of the drawing. However, it will be understood that the shape not only of the pad 2 but also of the pad 1 may be changed and varied to meet the requirements in practice as they may arise.

In order to secure the brace or strap 21 to the pad 1 I have provided the same with an opening 22 near one end thereof through which a screw 23 is adapted to be passed, which screw is in engagement with the screw threads 12 previously referred to. The said screw is provided with a flanged portion 24 which engages the strap or brace 21, as shown, and is also provided with a headed extension 25 which is adapted to be engaged with openings in the outer end of the said strap or brace.

It may happen that the stem 15 of the supplemental pad 2 may fit the opening in the stem 8 so closely as to prevent the ready removal of the same except by the use of means which may be employed for effecting such removal. In case it should become necessary the screw 22 may be removed and an elongated screw-threaded member, not shown, screwed into the opening of the stem 8 to cause the inner end thereof to engage the inner end of the stem 15 and push the same out of the opening of the said stem 8 and out of the opening 10.

By the employment of a pad structure comprising a main or body pad, such as that indicated by the reference numeral 1, and a supplemental pad such as that indicated by the numeral 2, the latter resting upon and projecting from the said main pad and having its inner face conforming to the shape of the outer face of pad 1, I have provided means whereby the efficiency of the action of the truss in the accomplishment of the purposes for which it is or may be employed is greatly enhanced. It is desirable that the supplemental projecting pad 2 be provided upon trusses which are worn by persons engaged in violent and heavy work or in violent exercises because its presence enables the truss to more effectually perform its function of closing an opening or rupture and preventing the descent or protrusion of an organ of the body through such opening or rupture. The ability to remove the supplemental pad 2 is of great advantage because the wearer of a truss of the construction embodying the invention and as illustrated may, when he discontinues the heavy work in which he may have been engaged or discontinues exercising violently, remove the said projecting supplemental pad and use only the pad 1. The surface of the pad 1, being larger and uniform in its curvature, perhaps would be more comfortable in

its pressure against the body than the pad 2, and if a person were not performing heavy work or exercising violently would operate to prevent descent or protrusion of any portions of the organs of the body through an opening or rupture.

It will be noted that the wearing surfaces of both of the pad members 1 and 2 are convexly curved, and it also will be noted that these surfaces are not, in the construction illustrated, spherical. It follows, therefore, that the radii of the wearing surfaces and different portions of the respective pad members 1 and 2 will or may be of different lengths.

It also will be noted that the inner surface of the small superposed wearing pad 2 is concave and that the curvature of the concavity is such as to permit or cause it to fit closely against the underneath surface of the pad 1, which, when the latter is in use alone, constitutes a part of the wearing surface.

Having thus described my invention, what I claim and desire to secure by Letters Patent is:

1. A truss pad comprising a relatively large pad member having a wearing surface of relatively large area, an anchor plate provided with an outwardly projecting central portion and an inwardly extended rim portion, the latter being imbedded within the said pad member and the said outwardly projecting central portion being provided with an inwardly extending hollow stem, and the said pad member being provided with an opening in its inner side in alinement with the opening through the said stem, a relatively small pad member adapted to be mounted upon the wearing surface of the said relatively large pad member, the said relatively small pad member being provided with a stem projecting from the inner side thereof, the said stem being so constructed as to frictionally engage with the opening of the said hollow stem and the opening in the inner side of the said relatively large pad member.

2. A truss pad structure comprising two pad members one of which is larger than the other, the smaller pad member being supported upon the larger pad member, the larger pad member having a centrally located opening extending therethrough, a bushing secured in the outer portion of said opening, said bushing having an opening extending lengthwise therethrough, and a stem projecting from the inner side of the said smaller pad, the outer end of which stem is provided with slots to divide the same into sections which are bent slightly outwardly to enlarge the said outer end, the said outer end extending into the inner end of said bushing and frictionally engaging the sides thereof to de-

tachably connect the smaller to the larger pad member.

In testimony that I claim the foregoing as my invention, I have hereunto signed my name this 7th day of September, A. D. 1928.

WALTER B. SEELEY.
